UNITED STATES PATENT OFFICE.

CHESTER BRADFORD, OF INDIANAPOLIS, INDIANA.

GRAIN ELEVATOR AND WEIGHER.

SPECIFICATION forming part of Letters Patent No. 732,335, dated June 30, 1903.

Application filed December 24, 1901. Serial No. 87,073. (No model.)

To all whom it may concern:

Be it known that I, CHESTER BRADFORD, a citizen of the United States, residing at Indianapolis, in the county of Marion and State 5 of Indiana, have invented certain new and useful Improvements in Grain Elevators and Weighers, of which the following is a specification.

The object of my present invention is to 10 provide in that class of grain elevators and weighers wherein the grain is elevated by an endless conveyer and wherein the weighing mechanism is first started into operation by a predetermined weight or quantity of grain 15 and wherein the operation is completed by positively-driven devices, including a continuously-moving part (usually propelled from a shaft of the elevator) and an intermittently-moving part, an improved engaging or 20 clutching device, whereby the continuously-moving part is engaged with and caused to drive the intermittently-moving part at the proper time and for the proper period, as will be hereinafter more particularly described 25 and claimed.

Referring to the accompanying drawings, which are made a part hereof, and on which similar reference characters indicate similar parts, Figure 1 is a side elevation of the upper end of an example of the type of elevator in question and the weighing mechanism carried thereby; Fig. 2, a side elevation of the other side thereof; Fig. 3, a vertical sectional view, on an enlarged scale, as seen 35 from the point indicated by the dotted line 33 in Fig. 1; Figs. 4, 5, and 6, transverse sectional views, on a still further enlarged scale, of the weigher-mechanism-operating counter-shaft and immediately adjacent parts as seen 40 when looking in the direction indicated by the arrows from the dotted lines 44, 55, and 66, respectively, in Fig. 3, showing especially the engaging or clutching devices, which are the particular feature of my present invention; and Fig. 7, a detail sectional view similar to a portion of Fig. 3, but detached and on the same scale as Figs. 4, 5, and 6.

The elevator proper is, generally speaking, of a well-known form, which it is unnecessary to describe at length. Briefly, the type shown comprises two tubes 1 and 2, a suit-

able head 3, and a lower part. (Not shown.) Through these parts the chain or belt 4, carrying flights or buckets 5, move continuously while the elevator is in operation. Upon 55 this structure the scale-beam 10 is suspended, which carries the grain-receiving box 11, and said box is arranged to be counterbalanced (with its load) by a weight 12, said box preferably being steadied by a link 13, pivotally connected to an adjacent stationary part, as the pipe 2. The mouth of the head 3 has a swinging gate 6, and the grain-box 11 has a swinging gate 14. These gates are respectively adapted to be actuated from an 65 intermittently-moving shaft 20 by suitable connecting-rods 7 and 16, respectively. So far the apparatus is substantially like former mechanisms for the purpose.

Upon the intermittently-moving shaft 20 I 70 mount a hollow shaft or sleeve 21, having a wheel or pulley 22 upon the outer end, by which it is driven, and provided with a clutch member 23 in the shape of a toothed wheel or pinion upon the inner end. This sleeve- 75 shaft 21 is driven continuously by a belt or chain 8 from the upper elevator-shaft 9 in a manner which is common to machines of this character. Surrounding the pinion-like clutch member 23 is an annular guard or 80 housing 28, which is secured fixedly in place (being preferably mounted on the bridge-tree or frame part, which carries the shaft-bearing) and has an open under side of a form and size adapted to receive the other 85 clutch member, as will be presently described. Fixedly mounted upon the shaft 20 is a hub 24, and pivotally attached to this hub is the clutch member 25, which is of a form adapted to swing up inside the guard or housing 28 90 into engagement with the pinion-like clutch member 23. This is carried upon the pivot 26 and is kept from improper sidewise motion by the jaws 27, so that when thrown up into engagement with the pinion-like clutch member 23 it will be strongly and accurately held 95 to position while doing its work. The opening in the annular guard 28 being at the under side, the clutch-finger 25 will when the force which raises it is withdrawn be caused 100 to drop out of engagement by its own weight. To better insure an instantaneous disengage-

ment, however, I may provide a spring 29, which is placed between said finger and the hub or part by which it is carried, as shown. The two positions of the finger and pinion-like clutch part are indicated by the full and dotted lines, respectively, in Fig. 7.

Extending out from the grain-receiving box 11 is a stop-arm 30, with which a corresponding arm 31 on the shaft 20 is normally in contact, and said shaft 20 is thus prevented from revolving until one of said arms escapes from its contact with the other, which happens when the grain-receiving box is filled, (and overcomes the counterbalancing-weight 12,) at which times it descends sufficiently to carry the contact-point of the arm 30 below and free from the contact-point of the arm 31. Secured also to the arm 30 on the grain-box 11 is a plunger 35, the lower end of which passes through a guide or ear e on an adjacent non-moving part. Mounted on a corresponding part at a point immediately below this plunger is a pivoted lever 36, the other end of which extends out under and forms a support for the clutch finger or member 25. The plunger 35 is so adjusted as to strike the lever 36 just as the grain-box reaches its lower-most position when the arm 30 carried thereby, has escaped from its engagement with the arm 31. The lever 36 is thus caused to throw the finger 25 up inside the annular guard or housing 28 and into engagement with a notch in the periphery of the pinion-like clutch member 23, which, as before stated, is continuously in motion. The shaft 20 is thus caused to revolve and through the connecting-rods 7 and 16 operates the gates or valves 6 and 14, as will be readily understood. The plunger 35 may, as shown, have a screw adjustment and is thus capable of being positioned with great accuracy. The lever 36 and finger 25 being both pivoted at or near one end will fall back promptly to their normal position when pressure thereon by means of the plunger is relieved. This happens instantly the grain-box is discharged of its load, as it then at once reascends to position to receive a fresh charge. The annular guard or housing 28 is cut away at the point where the finger 25 enters just sufficiently so that the escaping of engagement between the clutch parts will take place just before the arm 31 reaches and comes in contact with the stop-arm 30 on the grain-box at the time a full revolution of the parts is completed. Being in motion, however, and aided by the slight friction of the sleeve-shaft 21 on the shaft 20, the motion will continue until the arm 31 comes in contact with the arm 30, although with this device actual contact between these parts is not of great importance. This clutch mechanism is certain and positive in its operation, not depending upon friction or uncertain engagement to start it into operation, and withal is of a simple, durable, and inexpensive construction.

Having thus fully described my said inven-

tion, what I claim as new, and desire to secure by Letters Patent, is—

1. The combination, in a grain elevator and weigher, of a counterbalanced grain-receptacle bearing a stop, an intermittently-moving part adapted to be stopped and held at a predetermined point thereby until released, a continuously-moving part, a pinion-like clutch member carried by said continuously-moving part, a finger-like clutch member carried by the intermittently-moving part, a lever carried by an adjacent stationary part extending out under and adapted to move said finger-like clutch member, a strike carried by the grain-receptacle adapted to come into contact with said lever as said grain-receptacle descends and thus throw the clutch members into engagement, and a guard or housing surrounding the pinion-like clutch member and serving to hold the two clutch members into engagement until a revolution is completed.

2. A clutch for actuating the gate-operating mechanism in a grain elevator and weigher, consisting of a constantly-driven toothed wheel, a counter-shaft, a pivoted finger mounted on said counter-shaft and adapted to be thrown into engagement with said toothed wheel, a guard mounted on an adjacent stationary part and nearly surrounding said wheel but having one open side whereby said counter-shaft when said clutch is thrown into engagement is driven a single revolution and the gates thus once opened and closed, and means actuated from the grain-receptacle whereby said clutch parts are thrown into engagement as the receptacle descends.

3. The combination, in a grain elevator and weigher, of a suitable conveyer-trunk having a discharging-head at the top, an endless conveyer passing through said trunk, shafts and wheels over which said conveyer passes, a movable cut-off gate to said discharging-head, a scale-beam, a grain-receptacle mounted on said scale-beam and having a discharging-opening, a movable gate to said opening, a counter-shaft, a wheel revolvably mounted on said counter-shaft constantly driven while the elevator is in operation, a stop connection between the counter-shaft and the grain-receptacle which is in engagement when said receptacle is in its upper position but which becomes disengaged as said receptacle descends, connections running from the counter-shaft to the movable gates arranged to close one as the other opens, and means for throwing the said constantly-driven wheel and the counter-shaft into engagement (and thereby causing said shaft to be driven from said wheel) consisting of a toothed wheel revolving with said constantly-driven wheel, a guard encircling said toothed wheel except at one side where it is open, a pivoted finger secured to the counter-shaft, and an operating-rod actuated by the grain-receptacle as it descends when fully loaded for throwing said pivoted finger into engagement with said

toothed wheel at the same time the stop connections between the counter-shaft and the grain-receptacle become disengaged.

4. The combination, in a grain elevator and weigher, of the trunk, the discharging-head, a grain-receptacle, gates to said discharging-head and said grain-receptacle, a scale mechanism carrying said grain-receptacle, an intermittently-moving counter-shaft, connections from said counter-shaft to said gates whereby as said counter-shaft is revolved said gates are opened and closed, a constantly-moving clutch part driven from the elevator-shaft, a second clutch part carried by the intermittently-moving counter-shaft, and a strike carried by the grain-receptacle adapt-

ed to throw said clutch members into engagement at the moment said grain-receptacle becomes loaded and descends and to rise and thus permit said clutch members to become disengaged as the load is discharged and said receptacle thus reascends, the engagement of the clutch members being thus effected by the direct force of the descending grain-receptacle.

In witness whereof I have hereunto set my hand and seal, at Indianapolis, Indiana, this 21st day of December, A. D. 1901.
